UNITED STATES PATENT OFFICE.

LOUIS C. KRUMMEL, OF CLINTON, CONNECTICUT, ASSIGNOR TO CONTINENTAL MACHINE COMPANY, OF SYRACUSE, NEW YORK, A CORPORATION OF NEW YORK.

MULTIPLE DOUBLE-SEAMER.

1,151,478.

Specification of Letters Patent. Patented Aug. 24, 1915.

Application filed December 30, 1909. Serial No. 535,680.

To all whom it may concern:

Be it known that I, LOUIS C. KRUMMEL, a citizen of the United States, residing at Clinton, in the county of Middlesex, State 5 of Connecticut, have invented certain new and useful Improvements in Multiple Double-Seamers, of which the following is a description, reference being had to the accompanying drawing and to the letters 10 and figures of reference marked thereon.

The invention relates to new and useful improvements in multiple double seamers, wherein a plurality of double-seaming mechanisms operate continuously and one 15 after the other on can bodies, for the purpose of attaching an end to the can body.

An object of the invention is to provide a machine wherein a plurality of double-seaming mechanisms are brought one after 20 the other beneath a feeding device for feeding can bodies and can ends to said double-seaming mechanisms.

A further object of the invention is to provide a device wherein a plurality of double-seaming mechanisms are continuously operated, receiving a can body and can end at one side of the machine, which end is attached to the can body by the double-seaming mechanism during the rotation 25 of the machine, and which can body with the end attached thereto is discharged from the machine at a different point in its rotation.

A further object of the invention is to 35 provide a plurality of double-seaming mechanisms which are simultaneously carried bodily about a supporting shaft, and in which the seaming rolls of the double-seaming mechanisms are operated by stationary 40 cams during the travel of the double-seaming mechanisms.

A further object of the invention is to 45 provide a carrier or body rest which receives the can body and holds the same until it is properly chucked and ready for rotation in the seaming head, which carrier afterward withdraws so as to allow the can body to be rotated.

A further object of the invention is to 50 provide a device for double-seaming, in which the can body and end are rotated in contact with the seaming rolls, by means of a rotating chuck, and by means of a ro-

tatable supporting plate which engages the opposite end of the can body. 55

A still further object of the invention is to provide a multiple double-seaming device with a chute for feeding can bodies to the double-seaming mechanisms, together with a support moving with the double-seaming mechanisms, which automatically holds the can bodies in the chute, and allows the same to drop one at a time into the double-seaming mechanisms; and also to provide automatic means for feeding can ends one at a time to 60 a double-seaming mechanism. 65

These and other objects will in part be obvious, and will in part be hereinafter more fully described.

In the drawings, which show by way of 70 illustration one embodiment of the invention,—Figure 1 shows a side view of the entire machine with certain parts in section and certain parts removed, in order to more clearly show certain elements of the double- 75 seaming mechanisms; Fig. 2 is a vertical sectional view centrally through the machine, showing the seaming rolls and the carriers therefor, in side elevation; Fig. 3 is an end view of the machine; Fig. 4 is a sectional 80 view on the line 4—4 of Fig. 1; Fig. 5 is a sectional view through the chute for feeding the can bodies and the can ends; Fig. 6 is a detail in side elevation of the chute or conveyer for the can ends, and the controlling 85 mechanism therefor; Fig. 7 is a horizontal sectional view through the lower end of the conveyer or chute for the can ends and can bodies; Fig. 8 is a top plan view of the flattening roll and its carrier; Fig. 9 is a side 90 elevation of the same, with certain parts broken away and in section; Fig. 10 is a detail showing one of the removable washers for adjusting the position of the flattening roll; Fig. 11 is a top plan view of the 95 curling roll and its carrier; Fig. 12 is a side view of the same, with parts broken away and in section; Fig. 13 is a detail, showing the carrier for the chuck spindle, the seaming roll supporting studs and the stud for 100 supporting the body carrier; also showing the upper end of the brackets for supporting said carrier; Fig. 14 is a sectional view through the same; Fig. 15 is a top plan view of the same; Fig. 16 is a sectional view 105 through the supporting plate for the open

end of the can body and its carrier; Fig. 17 is an end view of said supporting plate; Fig. 18 is a sectional view through the stationary supporting shaft and the rotating 5 turret sleeve carrying the double-seaming mechanism; Fig. 19 is a plan view of the supporting plate and the segments carried thereby, which prevent the can bodies from entering the double-seaming mechanism until the double-seaming mechanism is properly placed relative to the feed chute; Fig. 10 20 is a side view of the same; Fig. 21 is a side view of the arm for preventing the operating cams from rotating; Fig. 22 is an 15 edge view of the same; Fig. 23 is a side view of the body rest or carrier and its supporting and operating means; Fig. 24 is an end view of the same; Fig. 25 is a longitudinal sectional view through the cams for operating the seaming rolls and the body support; Fig. 26 is a transverse section, showing the cams in side elevation; Fig. 27 is partly a 20 sectional view, and partly a side view of the support and operating cam for the member 25 engaging the open end of the can body; Fig. 28 is an end view of the cam for operating said support; Fig. 29 is a detail showing the can body as about to drop into the seaming station; Fig. 30 is a diagrammatic 30 view, showing in end view and side elevation, the position of the seaming rolls to the can body and can end, when the double-seaming mechanism is in the position A, Fig. 2; Fig. 31 is a similar view when the 35 double-seaming mechanism is in the position B, in Fig. 2; Fig. 32 is a similar view when the double-seaming mechanism is in the position C in Fig. 2; Fig. 33 is a similar view when the can is in position to be discharged from the machine; Fig. 34 is a diagrammatic view, showing the position of the 40 chuck and supporting plate, and also the body rest or carrier when the can body is received into the double-seaming mechanism; and Fig. 45 is a similar view, showing the carrier moved away from the can body and the chuck and end support in position to rotate the can.

In carrying out my invention, I have provided a supporting frame in which are mounted the various parts of my multiple double-seaming mechanism. Said supporting framework consists of a bed plate 1 from which rise brackets 2, 2, which brackets carry a stationary shaft 3 extending horizontally through the machine. The parts of my double-seaming mechanism are supported so as to rotate about the stationary shaft 3, and, as herein shown, I have provided four independent double-seaming mechanisms, or stations which are located substantially 90° apart. Each of said double-seaming mechanisms includes a body rest or carrier 5, which engages the can body and also the can end, when it is fed

into the double-seaming station or mechanism and supports the same until the supporting plate 6 engages the end of the can body, which is not to be closed and forces the can body on to the can end, and the can 70 end on to the chuck 7, as clearly shown in Fig. 35. The carrier, after the can body and can end have been properly engaged by the chuck and supporting plate, is moved away from the can body, so that the can end 75 and body may be rotated by the chuck 7.

The curling roll 8 is moved into engagement with the flange on the can end and can body, and performs the usual rolling of the flange, so as to form the double seam. The 80 flattening roll 9 is then brought into engagement with the seam and the same compressed and finished. The can bodies are fed to the double-seaming mechanisms by means of an inclined conveyer or chute 10. 85 Said chute is mounted on a bracket arm 11, secured to the bed plate 1 of the machine in any desired way. Said chute is preferably arranged so as to extend at an angle of substantially 45° to the vertical. 90

The chute, as clearly shown in Figs. 5, 6 and 7, consists of an angle bar 12, which is adjustably carried by the bracket arm 11. A plate 13 is spaced from the angle bar 12 by a spacing block 14, and said spacing 95 block is of sufficient height so as to form a groove or recess which receives the flange on the end of the can body. A second angle iron 15 supports the opposite end of the can body, and a plate 16 is spaced from the 100 angle iron 15 by a spacing block 17, similar to the spacing block 14. The can ends are also fed through the conveyer or chute 10. A plate 18 is spaced from the plate 16 by a 105 spacing block 19, and the can ends roll along the conveyer in the recess or pocket, formed between the plates 16 and 18. Bolts 20 secure the plates 15, 16 and 18 together, and said bolts 20 also pass through a standard 110 21, on which are mounted the upper rails of the chute or conveyer. The upper rails, as shown herein, consist of three plates, 22, 23 and 24, which are separated by suitable spacing blocks and so disposed as to form recesses or pockets which receive the upper 115 portion of the flange on the can body and the upper edge of the can end.

The plates 22, 23 and 24 are secured to the standard 21 by a bolt 25. The bolt 25 extends through a slot 26 in the standard. 120 The standard at its upper end is deflected laterally, and through the lateral extension 27 is a threaded bolt 28, which is rotatably connected at its lower end to an outwardly extending flange 29, carried by the plate 24. 125

It will be obvious that upon loosening the bolt 25 the bolt 28 may be adjusted and the plates 22, 23 and 24 moved toward or away from the plates 15, 16 and 18. The purpose 130 of this adjustment is to enlarge the chute

for different size can bodies and can ends. By connecting the plates together, the adjustment may be quickly made as all of the plates are simultaneously adjusted and retain their proper relation to one another.

The can bodies roll freely down the chute or conveyer, and if a seaming station is opposite the end of the chute, the can body will drop into the seaming station on to the body rest or support 5. If, however, the seaming station is not opposite the conveyer 10, then the segment 30 will receive the can body and serve as a support for the same until the seaming station is brought opposite the conveyer 10. The can ends, however, are held in the conveyer, and automatically released one by one, by means of a dog 31, which is pivoted to the plate 18 at 32. The dog 31 normally extends into the path of the can end, and holds the same in the chute or conveyer. A second dog 33 is also pivoted to the plate 18, and extends into the path of the can end. A short arm 34 is connected to the dog 31, and extends in a direction toward the conveyer. A short arm 35 is connected with the dog 33 and extends in a direction substantially parallel with the arm 34 and away from the conveyer. A link 36 connects the arms 34 and 35.

It will readily be seen that if the dog 33 be oscillated so as to move out of the path of the can end, the dog 31 will be moved in the opposite direction and into the path of the next can end, so that when one can end is released, the next succeeding can end is caught by the dog 31 and held until the dog 31 is thrown out of the path of the can end, at which time the dog 33 is then again thrown to such position as to engage and hold the can end released by the dog 31.

As a means for operating the dogs 31 and 33, I have provided a rock lever 37 which carries a roller 38 located in the path of travel of the supporting segments 30. A spring 39 engages the outer end of the rock lever, and normally holds the roller 38 pressed against the support 30. A link 40 connects the outer end of the rock lever 37 with the arm 35 of the dog 33. After the plate 30 passes the roller 38, the spring 39 will operate to oscillate the rock lever, and throw the dog 33.

The tripping mechanism for the can ends is located on the under side of the chute. When the segment 30 on one side of the seaming mechanism, passes the roll 38, said dog 33 will be thrown into the path of the can end, and the dog 31 released, allowing the can end to drop on to the dog 33. As soon as the end of the adjacent segment or support 30 engages the roller 38, the dog 33 will be thrown out of the path of the can end and allow the same to drop into the seaming mechanism on to the support 5.

The support or body rest 5 is formed with

arms 40 which are arranged at an angle to each other, so as to engage the can body at points at one side of the lower portion of the can body. The object of constructing the rest for the can body with arms disposed as above noted, is for the purpose of providing a body rest, which will receive and properly support can bodies of different sizes, as indicated in dotted lines in Fig. 24. The supporting arms 40, 40, as clearly shown in Fig. 24, have spaced magnetized steel ribs 41, on which the can body rests, and a wider magnetized steel rib 42, which is of slightly less height than the ribs 41, which receives the can end. These magnetic supports for the can body and can end, prevent the same from re-bounding when they drop from the chute on to the body rest, and hold the can body and can end in proper alinement with the chuck and rotatable supporting plate. Instead of a permanent magnet, it is obvious that an electro-magnet may be used.

The body rest 5 is mounted on a standard 43, which extends into a sleeve 44, and is secured therein by a pin 45, which extends through an opening in the sleeve, and a corresponding opening in the stem 43. I have provided the stem 43 with a plurality of openings, and by withdrawing the pin 45, the standard may be adjusted in the sleeve, so as to properly locate the body support for can bodies of different diameters.

The sleeve 44 slides vertically in a supporting bearing 46, mounted on the end of a stem 47, which is carried by a bracket 100 mounted to rotate with the machine. At its lower end, the sleeve 44 carries a roller 48. The roller 48 is adapted to travel on a cam 49, (see Figs. 1, 25, and 26). The cam 49 is held stationary, and is so constructed that the body support is raised to receive the can body just before the seaming station reaches the conveyer 10, and said body support remains raised until the can chuck and supporting plate have engaged the can body 110 and are in position for rotating the same. The body support then drops, as shown diagrammatically in Fig. 35, so as to allow the can body to be freely rotated. This movement of the body rest moves the magnet out 115 of contact with the can body and allows the free discharge of the cans from the machine. The body rest for the can will drop by gravity away from the can body, as soon as the roller 48 passes off from the raised portion 120 of the cam 49. In order, however, to cause the body rest to drop with certainty, I have provided a spring 5^a which is attached at one end to the body rest, and at its other end to the supporting plate 116.

As a means for rotating the can body and can end, in order to perform the double-seaming operation, I have provided the rotating chuck 7, which is mounted on the end of a chuck spindle 50, (see Figs. 1, 14 and 130

15). The chuck spindle 50 extends through a split bushing 51, which is secured to the carrier or bracket 52. Said carrier is split at its outer end, and provided with clamping bolts 53, which serve to clamp the bushing tightly in the carrier. Threaded collars 54 and 55 are screwed on to the spindle and hold the same in place and prevent the thrust of the chuck from longitudinally 10 moving the spindle in the carrier or supporting bracket. The chuck is secured in any desired way on the end of the chuck spindle. The chuck spindle is rotated by a gear wheel 56, driven in a manner herein- 15 after described. The carrier or bracket 52 for the chuck spindle, also has a socket 57, which receives the stem 47, supporting the bearing for the body support. Said carrier 52 is bolted to spaced arms 58, (see Figs. 4 20 and 13). The radial arms 58 are carried by a sleeve 59 (see Figs. 1 and 18), which sleeve 59 is rotatably mounted on the fixed shaft or axle 3 of the machine.

The carriers 52 mounted on the radial 25 arms 58, which as above noted, are carried by the sleeve 59, engage a gear ring 60, (see Fig. 4). Said gear ring is provided with a half threaded socket, 60^a which is adapted to register with a similar half threaded 30 socket 60^b formed in the carriers 52, and threaded bolts 61 engaging the two half sockets serve to hold the gear ring on the carriers 52. The gear ring 60 co-operates with a gear 61^a mounted on the main shaft 35 62, which in turn is mounted in bearings in the bed plate 1 of the machine. The main shaft 62 carries the ordinary friction clutch 63 at its outer end. Upon the rotation of the main shaft, the gear 61^a will in turn impart 40 a rotating movement to the gear ring, which through the carriers 52 and radial arms 58 will rotate the sleeve 59 on the stationary axle 3.

The sleeve 59 carries a bracket disk 64, 45 near its opposite end, which bracket disk is splined to the sleeve, so as to rotate therewith and move longitudinally of the sleeve. Threaded nuts or collars 65 engage the bracket disk 64, on each side thereof, and 50 hold the same in its adjusted position on the sleeve 59. The sleeve 59 is threaded to co-operate with the nuts or collars 65. The bracket disk 64 is provided with bearings, which are in line with the spindles of the 55 rotating chucks, and a sliding bar 66 is located in each bearing (see Figs. 1 and 16).

The sliding bar 66 is centrally bored and carries a bushing 67, which is held in the bar by a suitable set screw 68. A spindle 69 is carried by the bushing 67, and at its outer end supports a plate 70, which is adapted to engage the open end of the can body and support the same while it is being rotated by the rotary chuck. Said plate

70 is secured to the disk 71, which in turn 65 is threaded on the end of the spindle 69. The spindle 69 carries an enlarged head 72 at its inner end, which holds the spindle in its bearing. A wearing block 73 may be provided to take up the thrust and wear of 70 the spindle 69.

The plate 70 is adapted to fit the inner face of the can body. The disk 71 has a short neck, on which is mounted an ejecting plate 74. Springs 75 are located between 75 the disk 71 and ejecting plate 74, and normally hold said ejecting plate forced outward against the supporting plate 70. Said ejecting plate has a peripheral flange 76, which fits the outer surface of the support- 80 ing plate 70.

The sliding bar 66 carries a roller 77 at its opposite end, which runs in a cam groove 78, formed in a cam disk 79. The cam disk 79 has a socket 80, which receives a stud 81, 85 which stud projects from the disk 79 through a suitable opening in the standard 2 of the frame, and operates to hold the cam disk 79 from rotating with the sleeve 59. The cam disk 79 is mounted on the hub of the 90 bracket disk 64, and the collar 65 holds the same in place.

After the can body is fed on to the body support or rest 5, the bar 66 is moved forward by means of the cam groove 78, as the 95 sleeve 59 rotates, and the plate 70, together with the stripper plate 74, engages the open end of the can body and moves the same longitudinally, so that the can body is forced on to the can end and the can end forced on 100 to the rotating chuck 7, so that the can body and can end are then rotated by the chuck, the plates 70 and 74 rotating with the can body and chuck.

As above noted, as soon as the can body 105 and can end are properly placed on the chuck, the body rest 5 is lowered from contact with the can body.

The curling roll 8 is mounted in a carrier 82, which is pivotally carried by a stud 83 110 mounted in the socket 84 formed in the bracket or carrier 52 (see Figs. 11, 12 and 13). The stud 83 may be secured in the socket 84 by a set screw or any other similar means. The carrier 82 has a laterally projecting arm 85, in which is mounted a roll 86, which runs on a cam 87 mounted on the sleeve 59, and held from rotation, (see Figs. 1, 25 and 26). The cam 87 is so constructed 115 that as soon as the can body and can end are 120 properly seated on the chuck, and are rotated thereby, the curling roll is moved into contact with the flange of the can end and can body, and the double seam formed.

In order that the seaming roll 8 may be 125 adjusted to vary the pressure of the seaming roll on the flange of the can end, or for the purpose of engaging the can ends of differ-

ent diameters, I have mounted the seaming roll 8 on short spaced arms 88, which are pivoted at 89 in a recess formed in the carrier 82.

- 5 The bolt 90 is provided with an eye, which extends between the arm 88, and is secured thereto by a stud 91. The bolt 90 extends through a threaded sleeve 92, which is carried by a threaded socket in the carrier 82.
- 10 Said carrier at its outer end is split and provided with a clamping bolt 93. The threaded sleeve 92 has its end formed so as to receive a wrench, so that said sleeve may be adjusted in its supporting socket after the 15 clamping screw 93 has been released. When the sleeve is properly adjusted, the clamping bolt 93 serves to lock the parts in adjusted positions. The bolt 90 carries a nut 94 at its outer end, which holds the same in the adjustable sleeve 92.

The flattening roll 9 is mounted on a carrier 95, which is pivotally supported by a stud, 96, mounted in the socket 97 formed in the carrier 52, (see Fig. 13). The stud 96 25 may be secured in the socket 97 by a suitable set screw or any other similar means. The carrier 95 is provided with a roller 98, which coöperates with the cam 99 mounted on the sleeve 59 and held from rotation therewith. The cam 99 is so constructed that the flattening roll is brought into contact with the seam at about the time the curling roll finishes its operations, and said flattening roll leaves the seam so that the can may 30 be discharged from the machine when the can body reaches the lower side of the machine.

- The flattening roll 9 is mounted between short spaced arms 100, which are pivoted 40 in the recess in the carrier 95 on a short stud 101. A bolt 102 extends through a threaded adjustable sleeve 103, and has an eye 104, which is located between the spaced arms 100 and secured thereto by a pivot stud 45 105. The carrier 95 is split at its outer end, and has a clamping bolt 106. The threaded sleeve 103 is formed at its outer end with a nut 107, whereby said sleeve may be adjusted upon the loosening of the clamping bolt 106. 50 The bolt 102 carries threaded nuts 108, which engage the threaded sleeve 103, and limit the movement of the bolt 102.

It is often desirable to provide a yielding means for supporting the flattening roll, so 55 that the same may yield slightly when passing a side seam or some other irregularity in the seam being formed. In order to provide a yielding support for the flattening roll, I have surrounded the bolt 102 with a yielding collar 109, which may be of rubber or the like. When the pressure becomes too great 60 on the flattening roll, the rubber collar 109 will yield, allowing the roller to move away from the seam being flattened. When it is

desired to adjust the tension of the flattening roll on the seam, this may be accomplished by adjusting the position of the threaded sleeve 103.

It is often desirable to adjust the position of the seaming rolls for different sizes of can bodies, and this is accomplished by means of removable washers 111. The bolts 90 and 102 are slightly flattened adjacent the eyes, and the washers 111 are cut away at 112, (see Fig. 10), so said washers may be slipped over the flattened end of the bolts.

In order to hold the washers 111 in place, I have provided a pin or key 113, which passes through the washer and through the bolts 90 or 102. By removing the washer 80 111, and substituting washers of different sizes therefor, the position of the seaming rolls 8 and 9 relative to the respectively operating rollers 86 and 98, may be readily varied.

The cams 87 and 99 are splined to a sleeve 114, which carries the cam 49 for operating the body support. The sleeve 114 is secured to an arm 115, (see Figs. 2, 21 and 22). The arm 115 extends through a slot in the 90 bracket arm 11, and is secured thereto in any desirable way. The arm 115 will hold the sleeve 114 from rotating with the main sleeve 59, on which it is mounted. As the seaming rolls travel around with the sleeve 95 59, the operating rollers for the seaming rolls will engage the various parts of the stationary cams, and the seaming rolls will be operated.

A supporting plate 116, (see Fig. 19) is 100 bolted on the outer end of the supporting bearing for the body support (see Fig. 1), and rotates therewith about the stationary axle 3. Said supporting plate 116 carries the supporting segments 30.

After the can end has been attached to the can body, the sliding bar 66 is withdrawn by reason of the shape of the cam 78, and the stripper plate 76 will be forced outward by the springs 75, pushing the open 110 end of the can off from the supporting plate 70. In order to strip the can end from the chuck, I have provided an ejecting pad 117, which is carried by an ejecting rod extending through the chuck spindle. Said ejecting rod carries a collar 118, at its outer end and a spring 119 interposed between the chuck spindle and the collar, normally holds the ejecting pad housed within the chuck. Said rod has a hardened projection 120, 120 which is adapted to engage a cam 121 (see Fig. 1) carried by the frame of the machine, when the can body reaches the position in the machine where it is to be discharged therefrom. This cam 121 will force 125 the ejecting rod and ejecting pad inward, thus forcing the can end off from the chuck. As soon as the ejecting rod passes the cam

121, the spring will return it to normal position.

After the can end is attached to the can body, and is discharged from the seaming mechanism in the manner above stated, said can body drops into a chute 122, and is carried from the machine. A guard plate 123 extends from the chute 122, and serves to catch the can body if it is dropped from the machine before the seaming station reaches the discharge chute, and the rotating parts will carry the can body along and discharge the same through the discharge chute.

In Figs. 30 to 33, inclusive, I have shown diagrammatically the position of the seaming rolls relative to the can end for the various positions of the can body in its travel through the machine. When the can end and can body are received from the conveyer on to the body rest, the seaming rolls are both withdrawn, so that the can body and can end may be properly placed on the chuck. When the can body reaches the position indicated at A, (Fig. 2,) the curling roll is in the position shown diagrammatically in Fig. 30; that is, the curling roll is moved into contact with the flanges on the can end and the can body, and the flattening roll is still held away from the can end. When the can body in its travel reaches the position indicated at B, then the curling roll has performed its operation, as shown diagrammatically in Fig. 31, and the flattening roll is moving into operative position. When the can body in its travel reaches the position indicated at C (Fig. 2), then the seaming rolls have the position indicated diagrammatically in Fig. 32; that is, the flattening roll is finishing its operation, and the curling roll has moved away from the can end and can body. When the can body in its travel reaches the position to be discharged from the machine, then the seaming rolls are in the position indicated diagrammatically in Fig. 33; that is, both rolls are away from the can end and the can body, so that said can body may be dropped from the machine.

The chucks are rotated by means of a common gear 123^a, which engages each one of the chuck gears 56. The gear 123^a is carried by a hub 124 mounted on a reduced portion of the axle 3. The gear 125 is keyed to the hub 124, and in turn meshes with the gear 126, splined on the main shaft. It will be readily seen that the train of gears operating the chucks will greatly multiply the speed of the driving shaft, so that said chucks will be driven at a much higher rate than the sleeve carrying the seaming mechanisms.

In order to protect the operator from the gears for driving the chuck and the seaming mechanism, I have provided a shield 127,

which is mounted on the frame of the machine and extends over the gears and houses the same.

It will be noted from the above description, that I have provided a machine where in there is a carrier which has a plurality of seaming mechanisms or stations which operate independently of one another. The carrier is continuously rotated, receiving the can bodies and can ends while in motion, and the can ends are secured to the can bodies also while the carrier is in motion, and the cans with the ends secured thereto are discharged from said carrier. The carrier consists of the sleeve which is rotated from the main shaft and the bracket arms and bracket disk which support the chuck, the supporting plate coöperating with the chuck, the carriers for the seaming rolls and the bearing for the body rest. Said carrier is rotated as above noted, by a gear carried by the main shaft.

By using washers of a predetermined thickness, I am able to adjust very quickly the position of the seaming rolls relative to the chuck so that said rolls are adjusted for operation upon different sizes of can bodies. I also secure a like adjustment of both the curling roll and the flattening roll.

By adjusting the sleeves through which the bolts for the pivoted arms supporting the seaming rolls pass, I am able to secure an independent adjustment of the curling roll or the flattening roll relative to the carrier on which it is mounted.

It will be obvious that minor changes may be made in the details of construction, and the arrangement of parts, without departing from the spirit of my invention.

Having thus described my invention, what I claim as new and desire to secure by Letters Patent, is:—

1. The combination of a support rotating about a horizontal axis, a plurality of independently operating seaming stations carried by and moving with said support, a feed chute for can bodies, segments carried by said support and located between the seaming stations on which the can bodies rest whereby the can body is held from entering the seaming station until said seaming station is opposite said chute, and means for intermittently feeding can ends to the seaming stations.

2. The combination of a support rotating about a horizontal axis, a plurality of independently operating seaming stations carried by and moving with said support, a feed chute for can bodies, segments carried by said support, and located between the seaming stations on which the can bodies rest whereby the can body is held from entering the seaming station until said seaming station is opposite said chute, trip dogs for controlling the feed of the can ends

and a lever for operating said trip dogs having a roller bearing upon said segments.

3. The combination of a support rotating about a horizontal axis, a plurality of independently operating seaming stations carried by and moving with said support, each seaming station consisting of means for clamping a can body and end and for rotating the same, and seaming rolls for engaging the can end and forming a double seam, a feed chute for the can bodies, segments carried by said support and located between the seaming stations on which the can bodies rest whereby the can body is held from entering the seaming station until said seaming station is opposite said chute, a rest associated with each seaming station for temporarily receiving the can body and for supporting the same until engaged by the clamping means, and means for moving the rest out of contact with the can body after the same is clamped to permit the free rotation of the can body.

4. The combination of a support rotating about a horizontal axis and having a plurality of independently operating seaming stations, including means for clamping and rotating a can body and can end, a feed chute for can bodies, a rest located at each seaming station for receiving the can body and holding the same until it is clamped by said rotating means, and segments moving with said support and located between said seaming stations on which said can bodies rest when the seaming stations are out of alignment with the feed chute.

5. The combination of a support rotating about a horizontal axis and having a plurality of independently operating seaming stations, including means for clamping and rotating a can body and can end, a feed chute for can bodies, a rest located at each seaming station for receiving the can body and holding the same until it is clamped by said rotating means, segments moving with said support and located between said seaming stations on which said can bodies rest when the seaming stations are out of alignment with the feed chute, and means for intermittently feeding can ends to the seaming stations including a lever having a roller engaging said segments.

tating support, a plurality of seaming stations.

6. The combination of a continuously rotations carried thereby, means for rotating a can end and can body, a curling roll, a carrier for said curling roll, means for operating said carrier, a flattening roll, a carrier for said flattening roll, means for yieldingly and adjustably supporting the flattening roll on its carrier, and means for operating the carrier for the flattening roll.

7. A double-seaming mechanism including a seaming roll, a pivoted carrier for said seaming roll, means for oscillating said car-

rier, arms pivoted to said carrier and supporting said seaming roll, a sleeve threaded in said carrier, a bolt extending through said sleeve and pivoted to said arms, and interchangeable washers located between the head of said bolt and said threaded sleeve, whereby the position of the seaming roll relative to the carrier may be varied by changing the size of the washers.

8. A double-seaming mechanism including a pivoted carrier, means for oscillating the carrier, a seaming roll, arms pivoted to the carrier and supporting said seaming roll, a threaded sleeve mounted in said carrier, a bolt extending through said sleeve and pivoted to said supporting arms, a block of yielding material surrounding said bolt and located between the head thereof and the threaded sleeve, whereby said seaming roll may yield relative to its carrier.

9. A seaming mechanism including in combination, a rotating chuck engaging the end of the can body to be closed, an oppositely disposed rotatable supporting plate having means entering the open end of the can body and a stripper plate for stripping the open end of the can body from the supporting plate.

10. A seaming mechanism including in combination a rotating chuck engaging the end of the can body to be closed, an oppositely disposed rotatable supporting plate having means entering the open end of the can body and a stripper plate for stripping the open end of the can body from the supporting plate, and an ejecting pad located centrally of said chuck for stripping the can end from said chuck.

11. A seaming mechanism including in combination, a chuck for engaging the end of the can to be closed, means for rotating the chuck, means for holding said chuck from endwise movement, an oppositely disposed supporting plate having means adapted to extend within the open end of the can body, means for rotatively carrying said supporting plate, means for reciprocating the supporting plate endwise for engaging the can body and clamping the can body and the can end to said rotating chuck, and a stripper plate for stripping the can body from the supporting plate.

12. A seaming mechanism including in combination, a chuck for engaging the end of the can to be closed, means for rotating the chuck, means for holding said chuck from endwise movement, an oppositely disposed supporting plate having means adapted to extend within the open end of the can body, means for rotatively carrying said supporting plate, means for reciprocating the supporting plate endwise for engaging the can body and clamping the can body and the can end to said rotating chuck, a stripper plate for stripping the can body from

the supporting plate, and an ejecting pad located centrally of said chuck for stripping the can end from said chuck.

13. The combination of a rotating carrier, of a plurality of seaming stations carried thereby, said seaming stations including a chuck, means for rotating said chuck, a supporting plate coöperating with said chuck, said supporting plate having means adapted to extend within the open end of the can, an ejecting pad located centrally of said chuck, a stationary cam adapted to engage and operate said ejecting pad for stripping the can end from said chuck and yielding means for stripping the open end of the can body from the supporting plate.

14. The combination of a bed plate, standards carried thereby, a stationary horizontal axle mounted in said standards, a horizontally rotating sleeve carried by said axle, radial bracket arms mounted on said sleeve, a gear ring secured to said bracket arms, a main shaft, a gear carried by the main shaft and coöperating with said gear ring, a plurality of seaming stations supported by and movable with said rotating sleeve, and means movable with said rotating sleeve for clamping the can body and can end at each seaming station and rotating the same.

15. The combination of a bed plate, standards carried thereby, a stationary axle mounted in said standards, a rotating sleeve carried by said axle, radial bracket arms mounted on said sleeve, a gear ring secured to said bracket arms, a main shaft, a gear carried by said main shaft and coöperating with said gear ring, a plurality of seaming stations supported by and movable with said rotating sleeve, said seaming stations including a rotating chuck, a gear carried by each rotating chuck, a common gear mounted on said axle and engaging the gear carried by each of said chucks, and means operated from the main shaft for rotating said common gear at a higher rate of speed than that of the carrier.

16. The combination of a bed plate, standards carried thereby, a stationary axle mounted in said standards, a rotating sleeve carried by said axle, radial bracket arms mounted on said sleeve, a gear ring secured to said bracket arms, a main shaft, a gear carried by said main shaft and coöperating with said gear ring, a plurality of seaming stations supported by and movable with said rotating sleeve, said seaming stations including a rotating chuck, seaming rolls, carriers for said seaming rolls mounted on said radial bracket arms, cams loosely mounted on said sleeve and adapted to engage the carriers for the seaming rolls for oscillating the same, and means for holding said cams from rotating with the sleeve.

17. The combination of a bed plate, stand-

ards carried thereby, a stationary axle mounted in said standards, a rotating sleeve carried by said axle, radial bracket arms mounted on said sleeve, a gear ring secured to said bracket arms, a main shaft, a gear carried by said main shaft and coöperating with said gear ring, a plurality of seaming stations supported by and movable with said rotating sleeve, said seaming stations including a plurality of seaming rolls, carriers for the seaming rolls mounted on said radial bracket arms, a rest for the can body, means for moving said rest toward and from the axis of said sleeve, including a cam loosely mounted on said sleeve, cams loosely mounted on said sleeve and operating the carriers for said seaming rolls, and means for holding the cams for operating the rest and the seaming rolls stationary.

18. The combination of a rotating support including a sleeve, means for rotating said sleeve, radial bracket arms carried by said sleeve, a chuck mounted in each bracket arm, means for rotating each of the chucks, a bracket disk carried by the sleeve, a supporting plate for each chuck, mounted on said bracket disk, said bracket disk being splined to said sleeve, whereby it will rotate therewith and may be moved longitudinally thereof, and means for moving said bracket disk longitudinally of the sleeve for spacing the supporting plates from the rotating chucks for different sized can bodies.

19. The combination of a rotating support having a plurality of seaming stations, including a rest to receive the can body and can end, means for clamping and rotating the can body and can end, means for moving said rest away from the can body after the same is clamped, and means for adjustably connecting said rest to its moving means, whereby can bodies of different sizes may be operated upon at the seaming stations.

20. The combination of a continuously rotating carrier, having a plurality of seaming stations, including a rest for the can body and can end, a standard on which said rest is mounted, a sleeve engaging said standard, means for adjustably securing said standard at different heights in said sleeve, and means for reciprocating said sleeve, whereby the rest is moved toward and from the center of the seaming station.

21. The combination of a continuously rotating carrier, of seaming stations carried thereby, a chute for feeding can bodies and can ends to said seaming stations, said chute including spaced supporting plates, top guiding plates for the can bodies and can ends, and means for simultaneously adjusting said top guiding plates relative to said supporting plates.

22. A double seaming machine including in combination, a plurality of seaming rolls,

- a rotating chuck, and means for producing like and predetermined adjustments in each of the seaming rolls relative to the chuck.
23. In a seaming machine, the combination with a rotary carrier turning about a horizontal axis and having a plurality of horizontally disposed can receiving pockets, of a plurality of axially rotatable chucks on said carrier one at each end of each of said pockets, a plurality of seaming rollers mounted on said carrier, and direct pressure means for actuating said seaming rollers as the carrier rotates, said means including a cam and radial seaming roller slides, substantially as specified.
24. In a continuous rotary double-seaming machine, the combination with a continuously rotating carrier turning about a horizontal axis and having a plurality of horizontally disposed can pockets thereon, of a can body chute for delivering the can bodies one by one into the pockets of the carrier, a plurality of pairs of axially rotatable chucks mounted on the carrier one at each end of each of said pockets, a plurality of sets of double-seaming rollers mounted on the carrier, and an external annular gear for rotating the carrier, said annular gear surrounding the axes of said chucks on said carrier; substantially as specified.
25. In a continuous, rotary double-seaming machine, the combination with a can body chute, of a can head chute, a continuously rotating carrier turning about a horizontal axis and having a plurality of horizontally disposed can-body-receiving pockets, and a plurality of can head registering seats, a plurality of pairs of axially rotatable chucks mounted on said carrier one chuck at each end of each of said pockets, a plurality of sets of double-seaming rollers mounted on said carrier, said carrier having an external annular gear through which it is rotated, said annular gear surrounding the axes of said chucks on said carrier; substantially as specified.
26. The combination with a continuously rotating carrier turning about a horizontal axis and having a plurality of horizontally disposed can-receiving pockets, a chute for delivering the cans thereto, a plurality of chucks on said carrier, one at each end of each of said pockets, a plurality of sets of double-seaming rollers on said carrier, one set for each of said pockets, and an external gear on the carrier through which said carrier is rotated, said annular gear surrounding the axes of said chucks on said carrier; substantially as specified.

In testimony whereof I affix my signature, in presence of two witnesses.

LOUIS C. KRUMMEL.
